MULTIVIBRATOR CONTROL

Verne T. Braman, Long Island City, N. Y., assignor to Radio Corporation of America, a corporation of Delaware

Application April 26, 1929, Serial No. 358,287

2 Claims. (Cl. 250—36)

The present invention relates to synchronizing systems, and is particularly directed to a synchronizing arrangement suitable for use in connection with facsimile and television systems, although it is to be recognized that the use thereof is not restricted to such systems but that the invention may be used for the purpose of synchronizing two or more moving or vibrating bodies located at either adjacent or separated points. 5 Further, the invention relates to a method and means by which it is possible to apply a series of relatively low frequency synchronizing pulses for the purpose of synchronizing moving or vibrating bodies located at different points. 10

Therefore, as an object of my present invention, I have sought to provide a method and means by which moving or vibrating bodies located at different points may be synchronized, or by which synchronizing impulses of a constant 15 frequency may be applied for synchronizing moving or vibrating bodies, such as synchronous motors, driving impulse wheels or La Cour wheels, or driving tuning forks of low vibrational frequencies, or applied to any other well known and 20 suited uses.

As a further object of my invention, I have sought to provide a method and means by which sub-harmonic frequencies may be produced from 25 constant frequencies.

As a further object of my invention, I have sought to provide a multi-vibrator which may be used as a means for "splitting" frequencies, and thus producing fractional parts of the impressed 30 frequencies, or, what has become known in the art as the sub-harmonics of a basic impressed frequency.

Still other objects of my invention are to produce, in a method to be hereinafter set forth, an arrangement suitable for applying synchronizing 35 pulses to bodies which are to be synchronized, which is simple in its construction and arrangement of parts, a system which is cheap and convenient to install, a system which is efficient in its use, and a system which can be readily set up and conveniently operated.

Still other and further objects of my invention will at once suggest themselves and become apparent to those skilled in the art to which the invention relates by a reading of the following 40 specification taken in connection with the accompanying drawing, wherein, the single figure thereof shows a preferred form which my invention may assume, although it is to be understood that the invention is not limited to the construction illustrated, since various modifications may

be made therein in so far as such modifications fall within the spirit and scope of the present disclosure as defined by the hereinafter appended claims.

Now referring more particularly to the drawing, I have illustrated a tuning fork 1 as being of a substantially constant frequency and controlled as to its frequency by means of a thermostat control, or other suitable control (not shown), whereby the variations in temperature 60 tending to change the frequency of the fork are avoided, or the fork may be compensated as to changes in its frequency by, for example, forming a portion of the fork of two distinct metals which have different coefficients of expansion so that 65 the fork itself as it expands or contracts due to temperature changes may be made to change the frequency of the impressed impulses for driving the same in any preferred and desired manner. 70

As a driving means for the tuning fork 1, I 75 have shown an electromagnetic driving system 3, which is driven by means of a vacuum tube oscillator 5 upon which the fork frequency impulses are initially impressed through an electromagnetic pickup 7 associated with the fork 1. Impulses picked up by the pickup coil 7 are transferred through the primary winding 11 of the transformer 9 to the secondary winding 13 thereof, where they are impressed upon the grid member 17 of the oscillator 5, and across the circuit 80 including the grid member 17, the biasing battery 21 therefor, and the filament member 19. As shown, a source of potential 23 serves to provide heating current for the filament member, and the biasing battery 21 with its negative terminal 85 connected towards the grid member 17 provides a proper biasing potential for the grid. The output circuit of the oscillator 5 includes the plate member 15 and the drive coil 3, a source of plate potential B+, which in turn is connected through 90 the negative source of plate potential B— to the filament member 19. If desired, a meter for measuring the plate output current necessary to drive the fork may be inserted in the plate circuit 95 of the tube, as shown.

It is thus seen that when once the fork 1 has 100 been set into vibration impulses produced thereby are transferred to the grid circuit of the oscillator 5, and by amplification are then transferred to the drive means 3 for the purpose of keeping the fork in vibration, and the generated impulses from the fork are in turn again picked up by the pickup coil 7 so as to continuously provide a drive means for the fork. For the purpose of keeping high frequency currents from the source of plate 105 110

potential B+, I have provided a choke coil 27, and shunting the source of plate potential B+ and B-, I have provided a by-pass condenser 25 for the purpose of passing the higher frequency currents from the output circuit of the oscillator 5 back to the grid or input circuit.

Connected with the output circuit of tube 5 through a capacity coupling 29, I have provided a further amplifying tube 31 whose grid member 33 is connected with one side of the capacity coupling 29. The usual type of grid leak 41 connecting the grid 33, through a suitable source of biasing potential for the grid, and the filament member 37 at the tube 31 has been provided for permitting electrons to leak off the grid and thus prevent blocking of the tube 31. Output energy from the tube 31 flowing from the plate member 35, which is provided with a source of plate potential from a source B+ connected through the choke coil 43 to keep high frequency potentials from the source of plate potential, is then passed through a capacity coupling 45 and a resistance 47 to a multi-vibrator unit, including a pair of vacuum tube oscillators 53 and 55. In this connection, I have provided the resistor element 47, which may be variable where desired, for the purpose of adjusting the amplitude of the impulses supplied from the amplifier 31 to the vibrator unit.

The impulses transferred to the multi-vibrator unit including oscillators 53 and 55 are superimposed upon the output of these tubes through resistances 49 and 51 respectively, and energy flowing from the plate members 57 and 59 of the tubes 53 and 55 will then be subjected to a series of superimposed impulses from the tuning fork 1. Each of the vacuum tubes 53 and 55, respectively, are provided with the usual grid members 61 and 63 and filament members 65 and 67, which are heated, respectively, by the usual heating batteries 69 and 71. For the purpose of connecting the tubes 53 and 55 of the multi-vibrator system together, so that one tube reacts upon the other, I have connected in the plate circuit, including the plate member 57, of the tube 53, a capacity element 73 which is connected with the grid member 63 of the tube 55, and, similarly, to connect the plate 59 of the tube 55 with the grid member 61 of the tube 53, I have provided a similar capacity element 75.

It will thus be seen when frequencies proportional to the frequency of the tuning fork 1 are impressed upon the multi-vibrator system, including the oscillators 53 and 55, that these impressed frequencies from the fork change the potential balance of the vibrator system by changing the potential on both the plate and grid members of each of the tubes 53 and 55, and thus, as will be seen from a consideration of the drawing, since the vibrator system including the tubes 53 and 55 is in a most unstable condition, the superimposed impulses originating from the fork 1 will tend to stabilize the vibrator system and cause it to vibrate at its own natural period.

The natural period of the vibrator system is a function of and is determined by the valves, of the resistor members 49 and 51, the capacity elements 73 and 75, and the resistors 77 and 83 respectively, connected through a second set of variable resistors 79 and 81 in the input circuit of each of the tubes 53 and 55 respectively by a connection with the filament members 65 and 67 thereof, as well as the tubes 53 and 55 which may be provided.

Suppose, for example, and for the purpose of as-

suming valves by which a concrete illustration of operation may be given, that the vibrator system, including the oscillators 53 and 55, should have a natural period of vibration of 100 cycles per second, then, due to the inherent unstable character of the vibrator, it will be readily seen that this frequency might change and vary between a pair of limiting values of say, for example, 95 to 105 cycles per second. Now, if we assume for the purpose of further illustration that the fork 1 has a natural period of vibration of 400 cycles per second, then, if the frequency corresponding to the fork frequency is impressed upon the multi-vibrator system from the amplifier 31 through the capacity coupling and the resistor 47, to control the energy supplied to the vibrator from the fork, it will be seen that this impressed energy of the fork 1 tends to stabilize the vibrator system and cause it to vibrate continuously at its natural period. The natural period of vibration of the vibrator system may correspond to either the fork frequency, a harmonic thereof, or a subharmonic thereof. In the present case illustrated, it will be recognized, with the natural frequency of the vibrator system including tubes 53 and 55 assumed to be 100 cycles, and the fork frequency assumed to be 400 cycles, that the vibrator system will maintain a steady vibration at 100 cycles per second during periods when the fork frequency is superimposed thereon. This frequency, according to the example illustrated, is the fourth sub-harmonic or the quarter harmonic, of the natural fork frequency. Thus, a means for "splitting" frequencies and/or determining sub-harmonics thereof which are constant has been provided.

Now, in order to further amplify the subharmonic frequency corresponding to the natural period of vibration of the muti-vibrator system, I have provided amplifying tubes 95 and 97, whose filament members 99 and 101 are connected in parallel with the filament members 65 and 67 of the vibrator tubes 55 and 53. Each of tubes 95 and 97 have their filament members 99 and 101 heated from the sources of filament potentials 69 and 71 respectively. The grid member 91 of the amplifier 95 is connected with the grid member 61 of the tube 53, and also with the plate member 59 of the vibrator tube 55 by way of the capacity element 75, and similarly, the grid member 93 of the amplifying tube 97 is connected with the grid member 63 of the vibrator tube 55, and also through capacity element 73 with the plate member 57 of the vibrator tube 53. It will thus be seen that energy from the vibrator may readily be transferred to the amplifying system, including, the tubes 95 and 97, and therein amplified, so that amplified energy flowing from the plate members 103 and 105 of the amplifiers 95 and 97 respectively may be directed through the coils 109 and 111 of the relay member 107. Through a common connection to a source of plate potential B+, potentials are supplied to plate members 103 and 105 of the tubes 95 and 97. Thus, it will be seen that since the tubes 95 and 97 are connected in push-pull fashion with the vibrators 53 and 55, the armature 113 of the relay 107 will be caused to vibrate alternately between contacts 115 and 117 respectively in accordance with whether or not energy is being fed from the plate member of the tube 95 or 97.

As has been shown by the drawing, the armature 113 of the relay 107 is connected through a contact point 119 to a point of zero potential, the contact 115 is connected through a second contact member 121 to a point of negative poten-

tial, and, in a similar manner, the contact 117 is connected through a contact point 123 with a source of positive potential. Thus, as the armature 113 vibrates between the contacts 115 and 117 at a frequency corresponding to the frequency of the vibrator system, current will alternately flow in the circuit including the circuit connecting points 119 and 121, or the circuit including the contacts 119 and 123. In either or both of these circuits I have provided a second synchronizing member, which, for example, may be a 100 cycle tuning fork, or any of the other forms of constant speed or period systems above mentioned.

Referring to the above illustrated example for illustrating the principle of my invention, it will be readily seen that it is possible to accurately drive from the output of either the circuit including the contact 119 and 121, or the circuit including the contact 119 and 123, a fork of a frequency of 100 cycles in an accurate manner. It has long been recognized in the prior art that it is most difficult to accurately drive low frequency forks for the reason that the frequency thereof is rather unstable and due to the fact that it is practically impossible to provide a constant source of the desired frequency for applying driving impulses to a fork of low frequency in a manner similar to that shown in connection with the drive of the fork 1. A means has herein been provided whereby a relatively high frequency fork which can be conveniently controlled as to its frequency may be used to drive a second fork of a lower frequency, or instead of a fork, an impulse or La Cour wheel, or a low frequency synchronous motor of any desired type or style.

As a means for keeping high frequency currents generated in the vibrator system including the tubes 53 and 55 from the source of plate potential therefor, I have provided a choke coil 125 in series with the source of plate potential B+ for the oscillators 53 and 55 in a manner similar to that shown in connection with the oscillator 5.

While the accompanying diagram shows the

various sources of plate potential as being a plurality of different sources, it will, of course, be recognized that this has been illustrated merely for the purpose of simplifying the drawing, and it is fully within the scope and intention of my invention that all of these sources may be provided from a single common source of potential in which taps are appropriately taken off for supplying the desired plate potential to any of the vacuum tubes included in the system.

Other modifications of my invention than those herein disclosed will at once suggest themselves and become apparent to those skilled in the art to which the invention relates by a reading of the hereinafter appended claims.

Having now described my invention, what I claim and desire to secure by Letters Patent is the following:

1. An energy transfer system comprising a source of high frequency energy, a thermionic device serving as a low frequency unstable oscillator, a coupling tube connected between said high frequency source and said low frequency oscillator for transferring energy from said high frequency source to said low frequency oscillator and for preventing reaction upon said high frequency source from said low frequency oscillator, a thermionic amplifying system having its input circuit connected in parallel with the grid circuit of the low frequency oscillator, and a load circuit connected with the output of said amplifier.

2. A multi-vibrator unit comprising a pair of thermionic tubes having interconnected plate electrodes, a capacity connection between a grid electrode of each tube and the plate electrode of the other tube, means for supplying energy of predetermined frequency to the circuit including the plate electrodes of each of the said pair of thermionic tubes, a pair of push-pull amplifying tubes having the input electrodes thereof connected to the grid electrodes of the said first mentioned pair of tubes, and a load circuit connected with the output of said push-pull tubes.
